UNITED STATES PATENT OFFICE.

MINER M. FAIRCHILD AND GEORGE J. NIX, OF POSEYVILLE, INDIANA.

FENCE GUARD.

Application filed December 17, 1924. Serial No. 756,589.

To all whom it may concern:

Be it known that we, MINER M. FAIRCHILD and GEORGE J. NIX, citizens of the United States, residing at Poseyville, in the county 5 of Posey, State of Indiana, have invented a new and useful Fence Guard; and we do hereby declare the following to be a full, clear, and exact description of the invention, such as will enable others skilled in the art 10 to which it appertains to make and use the same.

The invention relates to fence guards of the type used in connection with wire fences and has for its object to provide supporting 15 brackets for a guard wire, which brackets are formed from pivotally connected members adapted to be attached to fence posts for supporting a guard wire spaced from the fence for preventing cattle from rubbing 20 against the fence.

A further object is to provide the horizontal members of the brackets with spaced 25 apertures for the reception of a pin on which the other bracket members are pivoted, and which pin and apertures allow adjustment of the bracket members in relation to each other for supporting the guard 30 wire at various elevations, or above the fence where it will not interfere with a plowing operation adjacent the fence, consequently allowing close plowing to the sides of the fence.

A further object is to provide the outer 35 ends of the horizontal members of the brackets with wire receiving slots disposed at an angle other than a right angle to the horizontally disposed members, thereby gripping and holding the guard wire when it is straightened after being placed in the slot.

With the above and other objects in view 40 the invention resides in the combination and arrangement of parts as hereinafter set forth, shown in the drawing, described and claimed, it being understood that changes in 45 the precise embodiment of the invention may be made within the scope of what is claimed without departing from the spirit of the invention.

In the drawing:—

Figure 1 is a perspective view of a portion 50 of a conventional form of wire fence showing the device applied thereto.

Figure 2 is a side elevation of one of the supporting brackets.

Figure 3 is a top plan view of one of the 55 supporting brackets.

Referring to the drawing, the numeral 1 designates a fence post of a conventional form of fence, and to which post may be secured in any conventional manner fence 60 wires 2. It has been found that live stock will break fence wires and otherwise damage the fence, and to obviate this difficulty a guard wire 3 preferably provided with bobs 65 4 is provided. Guard wire 3 is supported spaced from the fence by means of brackets 5 and consequently the cattle will be prevented from getting close to the fence and 70 damaging the same. Brackets 5 are secured to the posts 1, and extend outwardly therefrom. Each bracket 5 comprises an outwardly extending horizontally disposed arm 6, the inner end of which is secured at 7 to the post 1, and the outer end of which arm is provided with a wire receiving slot 75 8, at an angle other than a right angle to arm 6, and through which slot the guard wire 3 is passed to the transversely disposed wire receiving aperture 9. By disposing the wire receiving slot at an angle other than a right angle it will be seen after the wire has 80 been slightly bent or twisted and passed through the slot to the aperture 9, the wire will be held against upward movement.

Pivotal connected to the arm 6 and preferably on a removable pin 10 is a downwardly and inwardly extending brace arm 11, which brace arm is connected at 12^a to the fence post 1, and it will be seen that the brace arm will thoroughly and positively support the horizontally disposed arm 6. By providing the removable pin 10, it is obvious that the brace arm 11 can be easily detached from the arm 6 and moved to a position where the pin 11 will be received in any of the apertures 12 of the arm 6 for supporting the guard wire 3 at various elevations and particularly for supporting the wire above the fence as a whole when it is desired to plow close to the fence, and at 90 which time the guard wire may be easily and quickly positioned above the fence by simply removing the pin 10, moving the horizontal arm 6 upwardly and replacing the pins 10 through the upper ends of the brace arms 11, and one of the apertures 12 in the arms 6. It will also be seen that the device may 95 be easily and quickly returned to normal position as shown in Figure 1.

From the above it will be seen that a fence 100 guard wire bracket is provided, which may be easily and quickly applied to fence posts,

constructed in a manner whereby the wire supporting ends of the arms 6 may be positioned at different elevations, and at the same time the bracket attached to the side 5 of the post, thereby allowing said bracket to be attached to the post adjacent the lower ends thereof, and the guard wire positioned relatively close to the ground for protecting the fence from smaller animals, for instance 10 hogs.

The invention having been set forth what is claimed as new and useful is:—

A guard wire supporting bracket carried by a fence, said bracket comprising an outwardly extending arm secured to the side of 15

a fence post and provided with a plurality of apertures, an angularly disposed slot carried by the outer end of said arm and through which a guard wire extends, a brace pivotally connected to said arm and detachably connected thereto through one of the apertures thereof, said brace extending downwardly and inwardly and connected to the side of the post, said brace having its end which is connected to the arm obtusely 20 disposed and bifurcated.

In testimony whereof we have signed our names to this specification.

MINER M. FAIRCHILD.
GEO. J. NIX.
